UNITED STATES PATENT OFFICE.

FRANK E. WILLIAMS, OF LOS ANGELES, CALIFORNIA.

REINFORCING DEVICE FOR THE BACKS OF PAPER-COVERED BOOKS.

1,067,704.

Specification of Letters Patent.

Patented July 15, 1913.

Application filed April 30, 1912. Serial No. 694,221.

To all whom it may concern:

Be it known that I, FRANK EDWIN WILLIAMS, a citizen of the United States, residing at the city of Los Angeles, in the county 5 of Los Angeles and State of California, have invented new and useful Improvements in Reinforcing Devices for the Backs of Paper-Covered Books, of which the following is a specification.

10 In the use of magazines and like books having paper covers, the covers commence to tear at the ends of the back of the cover and become defaced and torn, and soon the whole cover comes off.

5 It is the object of my invention to provide a reinforcement of the cover at the ends of the back which will prevent the cover from becoming torn at this point.

A further object is to provide additional 20 means to fasten the cover to the signatures forming the book, signatures being the bunches of sheets containing the reading matter.

I accomplish these objects by the device 25 described herein and illustrated in the accompanying drawings forming a part hereof, in which:

Figure 1 is a perspective view of a paper 30 covered book provided with my improved reinforcing device. Fig. 2 is a view of the device before it is attached to the book. Fig. 3 shows differently cut signature flaps.

My device preferably consists of a flap or outside portion 5 and a shorter flap or inner side portion 6 made from a single piece of material, such as cloth or tough paper. When positioned for use the parts will be folded on each other on the dotted line 7-7 and that portion which is included between the 40 dotted lines 8-8 and 9-9 will be at the back of the signatures, and the central portions of the ends of the cover will lie therebetween and be pasted thereto except at the signature flaps. Signature flaps 10 and 11 45 are cut out of the inner portion 6 and when

positioned for use are pasted to the signatures. The remainder of the material is pasted to the cover, the outside portion 5 being on the outside and the inner portion 6 on the inner side and is pasted thereto 50 before the cover is put on the signatures. The signature flaps are pasted to the signatures at the same time the cover is put on.

By this device the cover is prevented from being torn and defaced at the ends of the 55 back and when it is opened out the flaps provide an additional bond between the cover and signatures.

Having described my invention what I 60 claim is:

1. A reinforcing device for paper covered books comprising a strip of material folded on itself forming outer and inner flaps, the central portions of the ends of the cover being positioned therebetween and pasted 65 thereto except at the signature flaps when positioned for use; and signature flaps partially severed from the inner cover flaps, said signature flaps being pasted to the sides of the outer ends of the signatures when 70 positioned for use.

2. As a new article of manufacture a reinforcing device for the backs of paper covered books comprising outer and inner flaps formed of a strip of material folded on itself 75 and having the central portions of the cover therebetween when positioned for use and being pasted to the outer and inner end portions of the cover; and signature flaps partially severed from the inner flaps, said 80 signature flaps being pasted to the signatures when positioned for use.

In witness that I claim the foregoing I have hereunto subscribed my name this 24th day of April, 1912.

FRANK E. WILLIAMS.
